UNITED STATES PATENT OFFICE.

CHARLES F. DUVAL, OF BOSTON, MASSACHUSETTS.

AUTOMATIC RAILWAY-SWITCH.

SPECIFICATION forming part of Letters Patent No. 528,867, dated November 6, 1894.

Application filed November 25, 1893. Serial No. 491,959. (No model.)

To all whom it may concern:

Be it known that I, CHARLES F. DUVAL, of Boston, in the county of Suffolk and State of Massachusetts, have invented certain new and useful Improvements in Automatic Railway-Switches, of which the following is a specification.

This invention relates to an improvement in automatically operated railway switches, and 10 may be said to consist broadly in the combination of normally disconnected switch-operating means adapted to be actuated by the passing car and adjustable to turn the switch either way, and electrical devices controlling the adjustment of said switch-operating means.

The invention is illustrated in the accompanying drawings, of which—

Figure 1 shows a plan view of a switch constructed in accordance with my invention. Fig. 2 shows a vertical section.

The same letters of reference indicate the same parts in both the figures.

In the drawings: the letter *a* designates the 25 rails of the main track; *b*, the rails of the switch; and *c*, the switch-point, which is of ordinary construction. This switch-point is engaged by an eccentric pin *d*, projecting from the upper end of a vertical rock-shaft *d'*, 30 which extends into a vault *d''* below the track and is supported in a bearing therein, an arm *d''* being affixed to the lower end of said rock-shaft and having a slot, which receives a pin *e* on a slide *e'*, fitting ways on the bottom of 35 said vault and adapted to be reciprocated therein.

An armature *f* is pivoted at its middle to suitable supports on the slide *e*, and electro-magnets *g* are supported in the vault *d''*, in 40 position to co-act with opposite ends of said armature. These electro-magnets will be suitably connected through the track-rails with a source of electricity, and will be arranged to be controlled by the motor-man by means of 45 a switch, so that either of the magnets can be energized at will.

The armature *f* is slotted, as at *f'*, on opposite sides of its pivot, and a pair of weighted levers *h*, hung in juxtaposition within the 50 vault *d''*, are provided at their lower ends with

projections *h'* adapted to engage the slots *f'*, and at their upper ends with noses *h''* engaging a head *i* on the lower end of a push-piece *i'*, which projects up through one of the track-rails and is adapted to be acted upon by a 55 wheel of the passing car.

The operation is as follows: The motor-man, by operating the switch, causes one of the electro-magnets to be energized, whereupon that end of the armature which is below 60 this magnet is attracted, and the slot of the armature is brought into engagement with the projection *h'* on the lower end of one of the levers *h*. A wheel of the passing car depresses the push-piece *i'* and thereby operates said 65 lever *h*, causing its projection *h'* to act against the end of the slot *f'* and move the slide *e*, and the switch-point *c* is shifted through its connections with the said slide, which have been previously described. While one arm of 70 the armature is engaged with one of the levers *h*, the other arm is disengaged from the other lever *h*, so that the movement of that other lever, caused by the depression of the push-piece *i'*, produces no effect on the slide *e*. 75

It is evident that other means might be employed to carry out the invention, and that the invention is not therefore limited in this respect.

Having thus described my invention, what 80 I claim as new, and desire to secure by Letters Patent, is—

1. In a railway switch-apparatus, the combination of a movable switch-point; a push-piece arranged for actuation by a passing car; 85 operating connections between said push-piece and the switch-point with provisions for turning said point in either direction and including an adjustable member whose position determines the direction of movement of 90 the switch-point under impulse of the push-piece; and electrical devices for establishing two different positions of the said adjustable member.

2. The combination of a switch-point; a 95 push-piece adapted to be actuated by the passing car; suitable connections between said push-piece and the switch-point adjustable to move the latter in either direction, said connections including two separate members 100

both in operative relation with the push-piece and adapted to be moved thereby in opposite directions, and a disconnecting member movable to engage either of said members; and 5 electro-magnets controlling said disconnecting member, substantially as described.

3. The combination of a switch-point, a slide operatively connected with said switch-point, a pivoted armature on said slide, electro-magnets adapted to co-act with opposite ends of 10 the armature, levers adapted to engage the said armature when attracted by the magnets

respectively, and a push-piece adapted to actuate said levers and to be actuated by the passing car.

In testimony whereof I have signed my name to this specification, in the presence of two subscribing witnesses, this 21st day of November, A. D. 1893.

CHARLES F. DUVAL.
